Des. no. 20,189

UNITED STATES PATENT OFFICE.

HENRY CLAY BASCOM, OF LANSINGBURG, AND FRANCIS RITCHIE, OF TROY,
NEW YORK.

DESIGN FOR A HEATING-STOVE.

SPECIFICATION forming part of Design No. 20,189, dated October 7, 1890.

Application filed September 8, 1890. Serial No. 364,350. Term of patent 3½ years.

To all whom it may concern:

Be it known that we, HENRY CLAY BASCOM and FRANCIS RITCHIE, citizens of the United States, residing, the said BASCOM at the village of Lansingburg, county of Rensselaer, and State of New York, and the said RITCHIE at the city of Troy, in said State and county, have invented and produced a new and original Design for Heating-Stoves, of which the following is a specification, reference being had to the accompanying drawing, forming a part thereof and consisting of a single figure, affording a view in perspective of our newly-designed stove.

15 The leading feature of our new design consists in the ornamentation of the various parts.

The base A of the stove is provided with a plain border-band A' around its lower portion on the sides. The front side of the base is also provided near its upper portion with a horizontal row of ribs A², the individual ribs extending diagonally across the row. The row of ribs is divided at its middle part by 25 an ornament A³, consisting of a raised portion having foliated branches. The corners of the base are each provided with a foliated ornament A⁴. The sides of the base are provided with upper border-ribs A⁵, together 30 forming a rectangular figure on the upper side of the base. The circular fire-pot A⁶ rises from the top of the base and is inclosed by the rectangle described by the ribs A⁵. Mounted upon the fire-pot is the cylindrical combustion-chamber A⁷. The combustion-chamber and fire-pot are provided at their line of junction with a radially-projecting flange A⁸, provided at its outer edge with a plain band A⁹, and intermediately of such band and combustion-chamber with two horizontal rows of openings A¹⁰ and A¹², one within and above 35 the other. The body of the combustion-chamber has a plain surface and is provided with two rectangular doors B and B', one above the other. The lower door B is provided with a central circular raised register portion B² and with a honeysuckle ornament B³ in each corner, also with a smaller honeysuckle or-

nement near the middle edge of each side. The upper door B' is provided with a horizontal row of oval mica openings B⁵ and foliated ornaments, one each side of the individual openings. The upper end of the combustion-chamber is surmounted by a top or cover, which has its middle horizontal division or zone C dome-shaped and encircled by a series of inverted honeysuckle ornaments C' and its lower horizontal division C² encircled on its upper part by a series of small foliated ornaments C³ and on its lower part by a plain band C⁴.

What we claim as new is—

1. The ornamental design for a heating-stove, herein shown and described, consisting of a base having on its upper outer surface raised portions or ribs, forming a rectangular figure, a circular fire-pot mounted upon such base and inclosed within such rectangular figure, a cylindrical combustion-chamber mounted upon such fire-pot, provided with two rectangular doors—one above the other—having foliated ornaments thereon, a circular flange projecting from the combustion-chamber at its line of junction with the fire-pot, provided with two horizontal rows of openings, and a dome surmounting the combustion-chamber and provided with horizontal rows—one above the other—of foliated ornaments.

2. In a design for a heating-stove, the ornamental design on the base, herein shown and described, consisting of a plain border-band on the lower portion, a foliated ornament on each corner, a horizontal row of ribs on the upper portion of one side, having the individual ribs diagonal to the row, a foliated ornament in the middle of the row of ribs, and border-ribs on the upper portion of the sides, together describing a rectangular figure.

3. In a design for a heating-stove, the design on a rectangular door, herein shown and described, consisting of a central circular raised portion, a honeysuckle ornament in each corner, and a smaller honeysuckle ornament near the middle edge of each side.

4. In a design for a heating-stove, the orna-

OVER

mental design on the top, herein shown and
described, consisting of a series of inverted
honeysuckle ornaments forming a row en-
circling the dome-shaped middle division of
5 the top, and a horizontal row of small foliated
ornaments encircling the upper part of the
lower division of the top.

In testimony whereof we have hereunto set
our hands this 6th day of September, 1890.

H. CLAY BASCOM.
FRANCIS RITCHIE.
